UNITED STATES PATENT OFFICE.

JOSEPH RESOWER AND AUGUST HECK, OF NEW YORK, N. Y.

DESIGN FOR A PENCIL.

SPECIFICATION forming part of Design No. 13,814, dated March 27, 1883.

Application filed December 1, 1882. Term of patent 7 years.

To all whom it may concern:

Be it known that we, JOSEPH RESOWER and AUGUST HECK, of New York, in the county and State of New York, have invented a new and original Design for Pencils, of which the following is a specification.

The design consists in a winding of thread upon the exterior of a pencil and a tuft of thread fixed to the end, whereby the pencil is caused to resemble a tassel.

The design also consists in a pencil provided with a projecting or convex portion wound with thread.

In the accompanying drawings, Figure 1 is a side view of a pencil embodying our design. Fig. 2 is a side view of another pencil embodying our design, and Fig. 3 is a side view of still another pencil embodying the design.

Similar letter of reference designate corresponding parts in all the figures.

The pencil shown in Fig. 1 is of cylindric form. It is wound externally with silk thread *a*, which may be of any desirable color, or of a number of colors. It imparts to the pencil a shiny and very rich appearance, as the pencil appears to be incased in silk. *c* is a tuft of silk, which causes the pencil to have the appearance of a tassel.

The pencil shown in Fig. 2 has a projecting or convex portion, *b*, near the inner end. This

portion and the cylindric portion are wound with silk. The projecting portion adds to the appearance of the pencil, as it relieves the same of the ordinary straight lines. A tuft of silk, *c*, is affixed to the inner or upper end 35 of the pencil, and imparts to the pencil the appearance of a tassel.

In the pencil shown in Fig. 3 the projecting or convex portion *b* only is wound with silk. It has a tuft of silk, *c*.

Each of the pencils is shown as attached to a thread, *d*, by which it is suspended.

These pencils are especially designed for dance programme cards, and as they assimilate to the appearance of tassels they will be sufficiently ornamental without tassels.

What we claim as our invention, and desire to secure by Letters Patent, is—

1. The design consisting in a winding of thread upon the exterior of a pencil and a tuft 50 of thread affixed to the end, substantially as specified.

2. The design consisting in a pencil provided with a projecting or convex portion wound with thread, substantially as specified.

J. RESOWER.
A. HECK.
